CLAIM

The ornamental design for combined toilet and toilet seat, as shown and described.

DESCRIPTION

FIG. 1 is a perspective view of a combined toilet and toilet seat showing my new design;

FIG. 2 is a right side elevational view thereof, the left side being a mirror image of the right side;

FIG. 3 is a front elevational view thereof;

FIG. 4 is a rear elevational view thereof; and,

FIG. 5 is a top view thereof.

The broken lines showing of a water tank in FIG. 2 is for illustrative purposes only and forms no part of the claimed design.

FIG. 1

FIG. 4

FIG. 2

FIG. 3

FIG. 5
